UNITED STATES PATENT OFFICE.

NATHAN LEAVY AND ABRAHAM H. LEAVY, OF NEW YORK, N. Y.

DESIGN FOR A COMBINATION TOILET AND CANDY BOX.

Application filed April 7, 1927. Serial No. 21,503. Term of patent 3½ years.

To all whom it may concern:

Be it known that we, NATHAN LEAVY and ABRAHAM H. LEAVY, citizens of the United States, residing at New York, in the county of New York and State of New York, have invented a new, original, and ornamental Design for a Combination Toilet and Candy Box, of which the following is a specification, reference being had to the accompanying drawing, forming a part thereof.

Fig. 2 is a plan view of the same.

We claim:

The original design for a combination toilet and candy box, as shown.

NATHAN LEAVY.
ABRAHAM H. LEAVY.
